UNITED STATES PATENT OFFICE.

GEORGE H. WAGNER, OF CEDAR FALLS, IOWA.

GAGE.

No. 823,378.

Specification of Letters Patent.

Patented June 12, 1906.

Application filed March 27, 1906. Serial No. 308,816.

To all whom it may concern:

Be it known that I, GEORGE H. WAGNER, a citizen of the United States, residing at Cedar Falls, in the county of Blackhawk and State 5 of Iowa, have invented certain new and useful Improvements in Gages, of which the following is a specification.

This invention relates to gages designed especially for use in holding a straight-edge 10 in the operation of laying the shingles, and has for its objects to produce a comparatively simple inexpensive device of this character which may be readily applied for use, one which will be securely retained in applied 15 position, but may be conveniently released when desired, and one wherein the gage-arm may be readily adjusted in the operation of properly positioning the straight-edge.

With these and other objects in view the 20 invention comprises the novel features of construction and combination of parts more fully hereinafter described.

In the accompanying drawings, Figure 1 is 25 a perspective view of a gage embodying the invention. Fig. 2 is a longitudinal section taken centrally through the gage and showing the same applied for use.

Referring to the drawings, it will be seen 30 that the gage member comprises a base member or piece 1, a spacing member or block 2, and a longitudinally-adjustable supporting member or piece 3, the spacing member 2, which is formed from a length of strap metal bent into shape, as shown, being attached to 35 the base-piece 1 by means of a rivet 4, while the supporting member 3, which is likewise composed of a length of strap metal, is provided with a longitudinal opening or slot 5, adapted to accommodate a screw 6, engaged 40 with the spacing-block 2 and equipped with a clamping-nut 7, arranged to act upon a clamping member or plate 8, having terminal flanges 9, which bear on the edges of the supporting member 3. The base-piece 1, 45 which constitutes an engaging member for retaining the device in position upon the roof, as seen in Fig. 2, is provided at its normally lower end with a pair of downturned sharpened engaging portions or teeth 10, 50 which when the device is applied are embedded in one of the shingles 11 and has its normally upper end sharpened to produce a knife-edge 12, which enters between the shingles, as shown, while formed at the upper 55 end of the supporting-plate 3 is a substan-

tially L-shaped engaging portion or head 13, designed to receive a straight-edge 14, it being understood in this connection that two of the gages are employed for supporting the straight-edge while laying the shingles, there 60 being formed on the spacing-block 2 by suitably bending the length of material of which the same is composed a downwardly-extending curved finger-piece 15, adapted to be grasped by the operator for lifting the device 65 to free the teeth 10 from the shingle 11 when the bevel of the gage is to be changed.

In practice the gage is attached to the roof by introducing the sharpened portion 12 of member 1 between the overlapping portions 70 of a pair of the shingles 11, the member being inserted a sufficient distance for the block 2 to contact with the butt of the uppermost shingle, after which the teeth 10 are embedded in the uppermost shingle for holding the device in place. The straight-edge 14 is next positioned on the supporting member 3, as shown in Fig. 2, and in laying the next course 75 of shingles the butts thereof are alined on the upper edge of the member 14, as indicated 80 by dotted lines in Fig. 2. It will be understood that after a course of shingles have been laid the gage members, a pair of which are, as before stated, employed for supporting the straight-edge, disengage and move 85 one step higher up, and the operation continued as heretofore explained. Furthermore, it is apparent that by releasing the thumb-nut 7 the supporting member 3 may 90 be adjusted longitudinally as desired for properly positioning the straight-edge to regulate the distances between the shingles.

Having thus described my invention, what I claim is—

In a device of the class described, a base 95 member, a spacing member or block attached to said base member and comprising a single length of material bent into shape to form a substantially rectangular body portion and a bearing finger-piece, a supporting member provided with an engaging head, and means for adjustably connecting the supporting member with the spacing-block. 100

In testimony whereof I affix my signature in presence of two witnesses.

GEORGE H. WAGNER.
